UNITED STATES PATENT OFFICE.

FRANK HINMAN PIERPONT, OF SALFORDS, HORLEY, ENGLAND, ASSIGNOR TO LANTON MONOTYPE MACHINE COMPANY, OF PHILADELPHIA, PENNSYLVANIA, A CORPORATION OF VIRGINIA.

LOW-QUAD-OPERATING MECHANISM FOR TYPOGRAPHIC MOLDS.

Application filed February 8, 1922. Serial No. 535,016.

To all whom it may concern:

Be it known that I, FRANK HINMAN PIERPONT, a citizen of the United States of America, residing at Salfords, Horley, in the county 5 of Surrey, England, have invented certain new and useful Improvements in Low-Quad-Operating Mechanisms for Typographic Molds; and I do hereby declare the following to be a full, clear, and exact description of the same, reference being had to the accompanying drawings, forming part of this specification, and to the characters of reference marked thereon.

This invention relates to type casting or 15 type casting and composing machines and particularly to such machines equipped with low quad molds and operating mechanism therefor, in which the mold is provided with a split blade comprising an upper or cut-off blade or section and a lower, main blade or section, so that such mold is capable of producing normal or full-height type bodies and also low quads or spaces short of full height.

25 The mold blade operating mechanism in commercial machines of this kind is usually controlled by mechanism operatively connected with the matrix clamping mechanism of the machine, the relative movements of 30 the main and supplemental blades to produce short type bodies being brought about by the presentation over the mold of suitably shaped matrices which produce a variation in the travel of the matrix clamping mechanism 35 as described for example in United States Letters Patent No. 828,450, No. 1,061,559 and No. 1,193,420. In these patents the matrix for operating the low quad mechanism is of such form as to lack the deep cone- 40 hole or cavity present in matrices for full type high bodies. In certain constructions, as for example, those shown in the second and third patents above mentioned, the main and cut-off blades are not coupled together 45 but are moved by separate or independent mechanism and the pressure acting to hold the main and cut-off blades back to dimension the mold for full-height or normal type bodies is different from that which acts on 50 the main blade when it alone is moved back

to dimension the mold for low type bodies, the cut-off blade being meanwhile retained in its forward position to close the top of the mold cavity.

When full height bodies are being produced, both blades are moved back to dimension the mold by their respective operating mechanisms and as in this position the rear end of the cut-off blade of the mold butts against a shoulder or offset on the main 55 blade, as shown, for example, in the first patent above mentioned, the force acting to hold the diminishing blades in open, dimensioning position is the combined force exerted by the two operating mechanisms. 60

When low quads or spaces are being cast, the cut-off blade is held forward and the main blade forced back by its operating mechanism to dimension the mold, so that the force acting on the dimensioning blade 70 is only that exerted by its own operating mechanism.

Under these circumstances there is a tendency for the mold to be setwise dimensioned 75 slightly less for low bodies than for high bodies of the same set dimension. It will be understood that the mold blade dimensioning pressure acts against an abutment backed by a plurality of wedges and not against an absolutely unyielding buffer: the 80 difference in pressure above referred to has the effect, therefore, to produce under commercial operating conditions variations in the set dimensions of high and low bodies and these variations, though extremely minute in any single instance, have a tendency 85 to produce measurable variations in the relative lengths of lines of type and thus interfere with the production of properly justified matter.

90 The present invention has for its principal object to provide a construction including an equalizing device or mechanism by which the force or pressure acting on the mold blade to dimension the mold is the same whether high or low type bodies are being produced.

95 Referring to the accompanying drawings:—

Fig. 1 is a side elevation showing the pres- 100

ent invention applied to or embodied in a mold and a matrix centering and clamping mechanism of a well known form of type casting and composing machine.

5 Fig. 2 is a plan view of the mold and the equalizing mechanism of the present invention.

10 Fig. 3 is an end elevation of the mechanism of Fig. 1 showing the parts in position for dimensioning the mold for producing low quads or spaces.

15 Fig. 4 is an elevation of part of the mechanism shown in Fig. 3, the parts being in position for dimensioning the mold for full height type bodies, and

Figs. 5 and 6 are plan views of a modified construction of the equalizing mechanism of the present invention.

20 The invention will be described herein as applied to mold dimensioning mechanism of the kind shown and described in United States Letters Patent 1,193,420, above mentioned, and in connection with a type-casting and composing machine such as is well-known as manufactured by Lanston Monotype Machine Company and is generally shown and described in United States Letters Patent 625,998. It is therefore deemed sufficient for the understanding of the present invention to designate the parts of the mechanisms of the earlier inventions most intimately connected with or cooperating with the mechanism of the present invention; for example, the mold A; the matrix case B; 25 the cross head C to which the matrix case and its supporting frame are coupled; the matrix case lever D; the matrix centering pin E; the main actuating or centering pin lever F, coupled by a link F' with the matrix case lever D, and by a head E' and spring E² with the centering pin E; the rod or slide G and its operating cam lever G' and spring G² reciprocating the main mold blade H against a variably positioned stop, all these parts being substantially as described in United States Letters Patent 625,998. As to parts shown in United States Letters Patent 1,193,420, mention may be made of the lever K for operating the cut-off or supplemental blade H'; said lever K being pivotally connected at one end to the centering pin lever F and being forced down by said lever F through the spring coupling L; the interponent M carried by the lever K so as to be capable of horizontal movement on its pivotal connection at M' with the lever K, and being normally held in one horizontal position by the spring M²; the projection N on the head N' carried by the centering pin E to control the position of the interponent M in a well known manner so as to operate one or the other of the two power actuated members O, O'; the lever P acted upon by the members O, O' and pivoted to the mold

A to operate the upper or cut-off mold blade H'.

As hereinbefore stated, full height type matrices have cavities or cone-holes in their upper ends for the reception of the centering pin E and when in connection with the patented mechanism referred to such a matrix is presented under the centering pin the latter travels down to its full extent and therefore the projection N does not operate the interponent M; so the latter is maintained by its spring M² in a position over the member or actuator O (Fig. 4). As the arm K descends pressure is applied to the actuator O and operates the cut-off 70 blade operating lever P to withdraw the cut-off blade H' until the rear end of the latter engages a shoulder on the main blade H which has been retracted by the cam operated lever G' acting on the power actuated member or rod G through the spring G². When both blades are thus retracted to dimension the mold the force acting to hold them retracted while a full height type is being cast is the force exerted by the rod G added to that exerted by the lever P. The low quad or space matrices, on the other hand, have no cavity or cone hole to receive the centering pin so that when such a matrix is presented under the pin E, the travel 75 of the latter is interrupted and the projection N acts on the interponent M to position it over the member or actuator O'. When the lever F descends, the actuator O' acts on the lever P to move the cut-off 80 blade H' forward and retain it in its forward position, the main blade H is retracted, as in the case for full height type bodies, but is maintained in its retracted position 85 only by the force exerted by the rod G. The low quad or space matrices, on the other hand, have no cavity or cone hole to receive the centering pin so that when such a matrix is presented under the pin E, the travel 90 of the latter is interrupted and the projection N acts on the interponent M to position it over the member or actuator O'. When the lever F descends, the actuator O' acts on the lever P to move the cut-off 95 blade H' forward and retain it in its forward position, the main blade H is retracted, as in the case for full height type bodies, but is maintained in its retracted position only by the force exerted by the rod G. Thus it will be seen that the force exerted 100 in dimensioning the mold differs as between high and low type bodies of the same set-wise dimension; this results in slightly different type dimension, as previously explained, and tends toward inaccuracies in 105 justification.

The present invention contemplates a construction comprising an equalizing mechanism whereby not only in making type high bodies including type-shoulder-high bodies but also in making low bodies, both the force exerted through the rod G and that exerted through the lever P act to hold the blades retracted. In the latter case, after the cut-off blade has been positioned to close the upper portion of the mold, the force exerted by its operating mechanism acts through said equalizing mechanism to add itself to the force exerted by the main blade operating mechanism to hold said main blade retracted; thus in either low or high body casting the forces acting upon the main blade to dimension the mold are 110 the same.

The above mentioned equalizing mechanism will now be described. The lever P is pivotally supported on a pressure equalizing lever Q at R, and the lever Q is pivoted at S on the mold body in the construction shown in Figs. 1 to 4 inclusive. One end of the lever P is embraced by the lower ends of the actuators O, O' while the other end enters an opening in the cut-off blade. The lever P has an opening T through which the pivot S of the lever Q passes, the opening T being large so that the lever P can act without being interfered with by the pivot S. The free end U of the lever Q rests in the path of movement of the main blade operating rod G and the latter is connected to the main mold blade by the pin J (Fig. 2).

When the blades are moved forward to eject a type body from the casting cavity of the mold the forward end G^a of the rod G is a little distance away from the free end U of the lever Q. The lever Q has a laterally extending shelf Q' to engage as shown in Fig. 5 with a hump P' on the lever P.

When a full height type body is to be cast, the centering pin E travels its full or normal distance and the interponent M is in position over the actuator O as shown in Fig. 4. As the matrix case lever F descends, the lever K is forced down carrying with it the interponent M and causing the actuator O to turn on its pivot V and operate the lever P. In this case the lever P turns on its pivot R until its hump P' strikes the shelf Q' of the lever Q; or the construction may be such that at this point the edge of the opening T bears on the pivot S of the lever Q. Thereafter with the levers at their least angular separation both the lever P and the lever Q turn on the pivot S so that the lever P moves the cut-off blade H' backward to dimension the mold. Meantime the main mold blade H has been moved back against its stop by the rod G. As already stated, when the cut-off blade H' has been moved back its rear end butts against a shoulder on the main blade H; in this retracted position the blades have their ends in alignment and the pressure exerted on the lever P and by it to the mold blade H' is added to the pressure exerted by the rod G.

When a low quad or space is to be cast the interponent M, as above stated, is moved over the actuator O' as shown in Fig. 3. As the lever F descends, the actuator O' is turned on its pivot V' and the lever P is operated in a direction reverse to that for high type. The lever P turns first on its end which engages the blade H' thus causing the lever Q to turn on its pivot S forcing the free end U of the lever Q against the forward end G^a of the rod G; thus the pressure applied to the lever P is distributed to the levers P and Q, causing them to swing open, the reverse pressure of the lever Q on the

main blade being practically equal to the forward pressure on the cut-off blade.

By the means just described the force acting to hold the blade H back is substantially the same when casting low quads as when casting full height type bodies.

According to the arrangement illustrated in Figs. 1 to 4 the levers P and Q are fitted into the body of the mold. When the arrangement is to be applied to existing molds it has been found convenient to pivot the levers to a bracket such as W which can be screwed, riveted or otherwise fastened to the mold body, as shown in Figs. 5 and 6, the levers in this construction being the same in function but having slightly different shape, as shown, to facilitate the application of the device to mechanism already in commercial use.

I claim:—

1. The combination with a typographic mold comprising main and cut-off blades, and separate mechanisms for operating these blades, of an equalizing device between the main and cut-off blades whereby the pressure acting on the main blade to dimension the mold is substantially the same when a low quad or space is being cast as when a full height type body is being cast.

2. The combination with a typographic mold comprising a main and a cut-off blade, of separate mechanisms for operating each blade, one of said mechanisms provided with an equalizing device acting on the blade operated by the other of said mechanisms whereby the force holding the cut-off blade in its forward position acts to help hold the main blade in its retracted position.

3. The combination with a typographic mold comprising main and cut-off blades, of a power actuated member for retracting the main blade, a separate power actuated member for operating the cut-off blade, a pressure equalizing lever pivoted to a stationary support and a cut-off blade operating lever pivoted to the pressure equalizing lever.

4. The combination with a low-quad mold provided with main and cut-off blades, of means for retracting the main blade, means separate from said first named means for advancing said cut-off blade, whereby said mold is adjusted for casting a low quad, and an equalizing device connected with said cut-off blade advancing means and applying to the main blade retracting means an assisting force substantially equal to the force exerted to advance the cut-off blade.

5. The combination with a low quad mold provided with main and cut-off blades, of separate, power-actuated members for operating each blade and an equalizing device interposed between said members, whereby in the position of the blades for casting a

low quad, said device applies to the main blade an assisting force to maintain it retracted which force is substantially equal to that applied to maintain the cut-off blade advanced.

6. The combination with a low quad mold provided with main and cut-off blades and

actuating means therefor of means interposed between the blades for distributing actuating power in opposite directions to 10 advance one blade and retract the other with substantially equal pressure.

FRANK HINMAN PIERPONT.
